UNITED STATES PATENT OFFICE.

ELIE W. LABOMBARDE, OF NASHUA, NEW HAMPSHIRE.

MECHANISM FOR FEEDING BLANKS, SHEETS, AND THE LIKE.

1,011,820.

Specification of Letters Patent.

Patented Dec. 12, 1911.

Application filed June 21, 1907. Serial No. 380,067.

To all whom it may concern:

Be it known that I, ELIE W. LABOMBARDE, of Nashua, in the county of Hillsboro and State of New Hampshire, have invented a new and useful Mechanism for Feeding Blanks, Sheets, and the Like, of which the following is a specification.

My invention relates to mechanisms for feeding blanks, sheets or the like, such for example as mechanism employed to feed paper box blanks to a box folding machine.

The object of my invention is to provide an improved mechanism of this character.

The main feature of my invention resides in the combination with a traveling conveyer adapted to support a stack of blanks or the like, of a gage adjacent to said conveyer and separated therefrom so as to leave a passage-way for a blank between the gage and conveyer and one or more stack-shaping stops for guiding the blanks under the gage.

In the best form of my invention two stack-shaping stops are employed one at each side of the gage for beveling the front end of the stack. That is, the blanks are deposited upon that portion of the conveyer that is traveling toward the gage and said conveyer acts to carry the blanks toward the gage and thereby forces the front end of the stack against the stack-shaping stops which shape or bevel the stack so that the bottom or first blank is guided under the gage. The bottom blank, being therefore unrestrained by the gage is fed forward under the latter by the traveling conveyer. The gage is positioned or adjusted with relation to the conveyer so that only one blank can pass thereunder at one time, the other blanks being held back until the first blank has been fed forward whereupon the next blank is fed forward immediately behind the first.

In the accompanying drawings: Figure 1 is a side elevation of a mechanism for feeding blanks or sheets embodying one form of my invention; Fig. 2 is a plan view of the mechanism shown in Fig. 1; Fig. 3 is a section on line 3—3 of Fig. 1; Fig. 4 is a section on line 4—4 of Fig. 3; Fig. 5 is a side elevation, on enlarged scale, of the gage; Figs. 6 and 7 are, respectively, side and rear elevations of an alternative form of stop.

Having reference to the drawings, the conveyer referred to above, is made up of a plurality of endless belts a supported by a driving drum a' and a roller a^2 journaled loosely at its ends in bearings on the frame

of the machine. The drum a' is on a shaft a^3 to which is fixed a pulley a^4 connected by a belt a^5 with a pulley a^6 fast to a driving shaft a^7 . Through the connections described 60 the shaft a^7 acts to continuously drive the conveyer a in the direction of the arrow in Fig. 4. Between the drum a' and roller a^2 is a loose shaft a^8 to which is fixed a plurality of flanged rollers a^9 that serve not only 65 to guide the belts a but also as supports for said belts.

The blanks are placed in a pile or stack A on the conveyer a and said conveyer feeds the blanks forward one at a time and delivers them to a pair of feed rolls b and b' which in turn feed the blanks farther forward and entirely away from the conveyer so that the second blank does not overtake the first blank. The roll b is made at its 75 ends with trunnions each journaled in a block b^2 sliding freely in a vertical slot or way b^3 provided on the frame of the machine, so that the weight of roll b which may be assisted by spring action, serves to 80 hold said roll against roll b' . The roll b' is journaled at its ends in the frame and at one end it carries a pinion b^4 meshing with a pinion b^5 on roll b and also with an intermediate or idle pinion b^6 driven by a gear 85 b^7 fixed to shaft a^7 . It will thus be seen that shaft a^7 also serves through the gear and pinion connection just described, to continuously drive the rolls b and b' in the directions of the arrows, Fig. 4, so that as soon 90 as the front end of a blank is presented to them by the conveyer a they engage said blank and feed it forward away from the conveyer.

The gage above referred to consists of a 95 hard steel blade c fastened in a holder c' by a clamping screw c^2 . Holder c' is made with a shank c^3 that is clamped to a bracket c^4 by a screw c^5 extending through a slot c^6 in shank c^3 . Journaled in the upper end of 100 shank c^3 is a screw c^7 whose lower threaded end engages a tapped hole c^8 in bracket c^4 . Between the head of shank c^3 and bracket c^4 is a spring c^9 inclosing screw c^7 . It will thus be seen that by loosening screw c^5 and 105 operating screw c^7 the blade c may be adjusted with relation to conveyer a according to the thickness of blank to be handled. The frame of the machine includes a bar d above and extending across the conveyer a 110 and this bar is made with a slot d' through which extends a stud d^10 threaded at its end

to receive a nut c^{11} by means of which bracket c^4 is clamped to cross-bar d .

Herein I have shown two stack-shaping stops f one at each side of gage c and each 5 of these stops is a tongue or strip of spring metal bent near its middle into the shape shown in Fig. 4. The upper end of each stop f is clamped to a bracket f' by a plate f^2 and screw f^3 . Each bracket f' is made 10 with a stud f^4 , Fig. 2, extending through slot d' in crossbar d , and carrying a nut f^5 by means of which the bracket is clamped rigidly to said cross-bar. Each bracket f' carries a screw f^6 bearing at its lower end 15 against the lower part of its respective stop f so that by adjusting said screw the space between the lower end of the stop and conveyer a may be accurately adjusted the resiliency of the stop serving to raise said 20 lower end and screw f^6 serving to force said end downward. A check-nut f^7 serves to lock screw f^6 in adjusted position and assists also in clamping the stop f to the bracket.

25 Variations in the shape of the blanks being handled require changes in the relation of the stops f to the gage c and as will be obvious the construction described permits of placing the gage and stops in any desired 30 relation by adjustment along slot d' . For the same reason it is necessary to adjust the stops f toward and from the stack A and therefore each stop is made with slots f^8 through which screws f^3 and f^6 extend so 35 that when said screw f^3 and nut f^7 are loosened said stops may be adjusted in this direction as required by the shape of blank.

Extending through the two stretches of 40 conveyer belts a are two pairs of cross-bars g fastened at their ends to the frame of the machine and supported by these cross-bars are two side gages j which position the stack A and guide the blanks as they are fed forward. On each gage j are mounted two 45 bolts j' whose lower ends extend down between bars g and are provided below the latter with heads j^2 . At their upper ends the bolts j' are threaded to receive hand nuts j^3 by means of which the gages are 50 clamped in position with provision for adjustment toward and from conveyer a .

To the cross-bars g are fixed two slotted bars h that have clamped to them by means of bolts h' , a frame h^2 carrying a loose 55 roller h^3 on which the rear end of the stack is supported at a greater elevation than the front end so that the blanks tend to slide by gravity down against the gage c and stops f by which they are properly positioned. Of course with small blanks the roll h^3 need not be used but it may be adjusted to a considerable extent with relation to the gage a and stops f according to the 60 size of blank by loosening bolts h' and adjusting the latter along bars h . Pins h^4 on

frame h^2 by engaging bars h prevent frame h^2 swinging on bolts h' . The adjacent flanges a^{91} of the two middle rolls a^9 are enlarged to form a wheel which serves as a rigid abutment rotating at the same speed 70 as the belts a and as shown in Fig. 3 this wheel a^{91} projects up through the conveyer and coöperates with gage c in controlling the feed of the blanks. The lower ends of the stack shapers f are practically in contact with the conveyer belts a and therefore when a blank is carried forward by the latter it is forced past said shapers f which yield to allow its passage as does also the 75 material of the conveyer a which is made 80 of a yielding material such as rubber composition.

Different styles of paper box blanks vary greatly in outline, some having a straight side which can be placed at the front of the 85 stack so as to require the lower ends of shapers f and gage c to be set in alinement over wheel a^{91} and rolls a^9 . On the other hand the edges of the blanks at the front of the stack will sometimes be made up of 90 notches and tongues so that the shapers f will be offset with relation to gage c , that is they will be set to the left or to the right (Fig. 4) of the gage. Therefore it will be 95 clear that in order to adapt the machine to handle blanks of different sizes and shapes, I have provided a structure that very conveniently provides for universal relative adjustment of the shapers f and gage c as well as individual adjustment of 100 said parts for blanks of different thickness. A peculiar feature of the gage c is that its lower blank engaging end is a knife edge extending transversely of the carrier so that the passageway for the blank is concentrated so to speak at the edge of the knife and moreover the friction on the top of the 105 blank is reduced to the minimum.

Located between the gage c and the rolls b , b' is a loose roller m extending across 110 and resting upon the top stretch of carrier a so that the movement of the latter constantly rotates said roll. This roll m is made at its ends with trunnions turning 115 freely in vertical slots provided in the lower ends of brackets m' fixed to bar d . As the advance end of a blank is brought forward by carrier a it passes under roll m which holds said advance end down onto the carrier and guides it accurately between the two rolls b , b' , said roll m yielding upwardly as the blank passes under it. The peculiarity of this roll m is that it is constantly in motion at a surface speed the same 120 as the carrier so that when it engages a blank the latter is not retarded or displaced by contact with a roll normally at rest as heretofore.

Figs. 6 and 7 show another form of stack-shaping stop wherein, instead of the resili- 130

ent tongue f above described a steel roll k is provided. This roll k is clamped rigidly by a bolt k' to a bar k^2 secured with provision for vertical adjustment to a bar k^3 5 which in turn is fastened with provision for horizontal adjustment to a bracket k^4 adapted to be mounted on bar d . Clamped to roll k by bolt k' is a deflector k^5 which bevels the stack like the inclined tongues f . 10 The blank engaging surface of roll k is roughened by nurling as shown in Fig. 7 and the purpose of this is to cause the exposed surface of the roll between the lower end of the deflector k^5 and carrier a to 15 properly restrain and hold back all of the lowermost blanks of the stack except the bottom blank. Besides shaping the stack the deflector k^5 serves to guide the front ends of the blanks under roll k and prevent 20 clogging.

What I claim is:

1. In a machine for feeding box blanks or the like the combination of a conveyer on which a stack of blanks are supported; a 25 gage in front of said stack for controlling the feed of the blanks; one or more stack-shaping stops alongside said gage; a rotatable support across and beneath the conveyer to support the latter adjacent the 30 stops; and a rotatable wheel projecting through the conveyer to coöperate with the gage.

2. The combination with a conveyer adapted to support a stack of blanks of a 35 stack-shaping stop consisting of an inclined tongue of spring metal; a bracket to which said tongue is fastened at one end with the

other end of the tongue coöperating with the conveyer, and a screw engaging the tongue intermediate its ends for adjusting 40 the lower end of the tongue with relation to the conveyer.

3. In a feed mechanism of the character described the combination of a conveyer adapted to support a stack of blanks; one or 45 more stack-shaping stops in front of the stack against which the latter is held by the movement of the conveyer and coöperating with the conveyer to yieldingly oppose the feeding of a blank; a gage and an 50 abutment coöperating therewith to control the feed of the blanks, said gage and abutment permitting only a single blank to pass at a time and said conveyer acting frictionally to carry said blank between the 55 gage and abutment and force it past the stack-shaping stops; and means to provide for forward and rearward relative adjustment between the gage and the stop or stops in a direction parallel to the line of feed 60 and according to variation in the shape of blank being handled.

4. In a machine for feeding box blanks or the like the combination of a conveyer on which a stack of blanks are supported, a 65 gage at the front end of the stack to control the feed of the blanks; a stop at the front end of the stack; and an idle roll supporting and permanently elevating the rear end of the stack.

ELIE W. LABOMBARDE.
